UNITED STATES PATENT OFFICE.

ROBERT S. MOORE AND JAMES LEE SIMMONS, OF WASHINGTON, DISTRICT OF COLUMBIA, ASSIGNORS TO THE GYRO MOTOR COMPANY, OF WASHINGTON, DISTRICT OF COLUMBIA, A CORPORATION OF THE DISTRICT OF COLUMBIA.

GAS-ENGINE.

1,019,513.

Specification of Letters Patent. Patented Mar. 5, 1912.

Original application filed November 1, 1910. Serial No. 590,236. Divided and this application filed March 30, 1911. Serial No. 617,855.

To all whom it may concern:

Be it known that we, ROBERT S. MOORE and JAMES LEE SIMMONS, citizens of the United States, residing at Washington, in 5 the District of Columbia, have invented certain new and useful Improvements in Gas-Engines, of which the following is a description, reference being had to the accompanying drawing and to the figures of reference 10 marked thereon.

The invention relates to new and useful improvements in gas engines, and more especially to gas engines of the rotary cylinder type.

15 An object of the invention is to provide means for properly lubricating the walls of the piston head.

A further object of the invention is to provide means for preventing the throwing 20 of the lubricating oil through an intake valve located in the piston head, which receives its charge from the supporting casing in which the lubricating oil is placed.

This application is a division of our application Serial No. 590,236, filed November 1st, 1910.

In the drawings which show by way of illustration one embodiment of the invention; Figure 1 is a plan view with parts in 30 section, showing a rotary engine having the improved oil guard applied thereto. Fig. 2 is an end view of the oil guard.

The rotary engine as shown in the drawings, consists in a general way of a casing 1, 35 to which is attached as herein shown, five cylinders 2, which may be of any desired construction. It is also obvious that any number of cylinders or a single cylinder may be used. The casing 1 is mounted to rotate 40 about a shaft 3, which is stationary and carries a crank shaft 4. In each cylinder is a piston head 5, to which is pivoted a piston rod 6. The piston head 5 is preferably cut away as at 7 so as to form bearing portions 45 8 and 9. Secured to the inner end of the piston head is the improved oil guard 10. Said oil guard as herein shown is formed with a cylindrical portion 11, which is threaded or otherwise secured to the inner 50 reduced end of the piston head. Said oil guard also has a tapering portion 12, which is shaped as the frustum of a cone for the purpose of forming an inclined wall which

receives a coating or film of the lubricating oil, and conveys the same between the outer 55 wall of the piston head and the inner wall of the cylinder. Said oil guard is also provided with a closed end 13 which is slotted at 14 to allow the piston rod to move angularly relative to the piston head during the 60 rotation of the cylinder.

The piston head is preferably provided with an intake valve 15 so that the explosive gases may be led from the casing through the piston head into the cylinder. Said cylinder is also provided with an exhaust valve 16 preferably located in its outer end so that during the rotation of the cylinder, the centrifugal force acting upon the gases will aid in carrying the same through the intake 70 valve into the cylinder, and will also aid in carrying the burnt gases out through the exhaust valve.

In an engine of this type, it is found that when the lubricating oil is placed in the casing and drawn outwardly to lubricate the piston head, that there is a great loss of the lubricating oil as the same is carried by the centrifugal force through the intake valve into the cylinder and then through the exhaust valve. The improved oil guard herein shown, prevents to a large extent the escape of the lubricating oil through the intake valve, and directs the same in a thin layer to the outer wearing surfaces of the piston 80 head.

It is obvious that from certain aspects of the invention, the oil guard herein shown may be used in connection with engines wherein the intake for the explosive gases 90 is of an entirely different character and that also said oil guard may be utilized in connection with engines of the non-rotating type as where ever it may be used it will serve 95 the purpose of accumulating a film of lubricating oil and feeding the same to the proper place on the piston head.

Having thus particularly described our invention, what we claim as new and desire to secure by Letters Patent, is:—

1. The combination of a cylinder, a piston reciprocating in said cylinder and an oil guard connected to the piston and movable therewith for directing the lubricating oil to the outer face of the piston.

2. The combination of a cylinder, a piston

100

105

reciprocating in said cylinder and an oil guard connected to the inner end of the piston and having an inwardly projecting portion shaped as the frustum of a cone to receive and guide the lubricating oil to the outer surface of the piston.

3. The combination of a cylinder, a piston reciprocating therein, a piston rod pivotally connected to the piston, and an oil guard connected to the inner end of the piston and having an inwardly projecting portion shaped as the frustum of a cone to receive and guide the lubricating oil to the outer surface of the piston, the inner end of said oil guard being closed except for a slot formed therein to permit the operation of the piston rod.

4. The combination of a revolving cylinder, a piston reciprocating therein, an intake valve in the piston, and an oil guard connected to the piston and movable therewith for directing the lubricating oil to the outer surface of the piston.

5. The combination of a revolving cylinder, a piston moving therein, an intake valve in the piston, and an oil guard connected to the piston and having an inwardly projecting portion shaped as the frustum of a cone, to direct the lubricating oil to the outer surface of the piston. 25

6. The combination of a revolving cylinder, a piston reciprocating in said cylinder, a piston rod pivotally connected to said piston, an intake valve in said piston, and an oil guard connected to the piston and having an inwardly projecting portion shaped as the frustum of a cone, the inner end of said oil guard being closed except for a slot to allow the operation of the piston rod. 30 35

In testimony whereof we affix our signatures, in presence of two witnesses.

ROBERT S. MOORE.
JAMES LEE SIMMONS.
